INVENTOR

UNITED STATES PATENT OFFICE.

CHARLES H. UPTON, OF LA GRANDE, OREGON.

PIN-GUARD.

1,075,520.

Specification of Letters Patent.

Patented Oct. 14, 1913.

Application filed September 18, 1912. Serial No. 721,021.

To all whom it may concern:

Be it known that I, CHARLES H. UPTON, a citizen of the United States, and resident of La Grande, Union county, State of Oregon, 5 have invented certain new and useful Improvements in Pin-Guards, of which the following is a specification.

This invention relates to certain improvements in pin guards adapted for use in 10 protecting the points of hat pins, scarf pins and the like, to hold the pin in position and thus prevent it from being lost, and also to prevent accidental injury by the point of the pin.

15 The object of my invention is to simplify the construction and reduce the cost of manufacture of pin guards of this character, without reducing the effectiveness.

In my improved pin guard, I so mount a 20 flat spring that the pin, in being inserted into the guard, passes between adjacent coils of the spring so as to spread them apart. This distortion of the spring causes the latter to effectively grip the pin and hold the 25 guard in place.

Reference is to be had to the accompanying drawing forming a part of this specification, and in which the same reference characters indicate corresponding parts in all 30 of the views.

Figure 1 is an end view of a pin guard embodying my invention, and Fig. 2 is a side elevation of the same with a portion of the casing broken away.

35 Referring to the drawings it will be seen that my improved pin guard consists of a casing 1, one end of which is closed and the other end open. Adjacent its open end the casing 1 is provided with a groove or bead 40 5 which forms a seat or retaining means for the outer coil of a flat spiral spring 4, the inner end of which is bent at right angles to the plane of the spring and extends through the center of the casing to the opposite or 45 closed end thereof and thus forms a shaft 2 which supports the central portion of the spring.

At a point intermediate its ends the casing is provided with a second groove or bead 6 50 which forms a seat of the outer coil of a flat

spiral spring 7, the inner end 8 of which is secured to the shaft 2 at the flattened portion 3 thereof, in any suitable manner, whereby the central portion of the spring 7 will be supported by the shaft. 55

In using the guard, it is forced over the point of the pin and held in place thereon by the tension of the coils which grip the pin.

The spring 7 is preferably made of smaller wire than the spring 4 and the coils are 60 closer together so that the springs exert different gripping actions on the pin. The guard is intended for use primarily on hat pins and frequently the point of the pin projects only a short distance through the 65 hat. Under these circumstances the closer spacing of the coils of the spring 7 enables the latter to grip the tapering portion of the pin.

Having thus described my invention what 70 I claim and desire to secure by Letters Patent is,

1. A pin guard comprising a tubular body having one end closed and the other end open and a plurality of spaced grooves 75 or beads in the wall thereof, flat spiral springs having their outer coils arranged in and supported by said grooves, and a shaft or rod secured to the central portions of said springs and engaging the closed end of the 80 tubular body.

2. A pin guard comprising a tubular body having one end closed and the other end open, a flat spiral spring arranged in said body at the open end thereof and having its 85 inner end turned at right angles to the plane of the spring and extending longitudinally of the body and engaging the closed end thereof, and a second spiral spring within said body spaced from the first spring and 90 having its inner end secured to said longitudinally extending portion of the first spring.

In testimony whereof I affix my signature in presence of two witnesses.

CHARLES H. UPTON.
